DUMPING DEVICE FOR TRUCKS

Bertron G. Harley, Saco, Maine, assignor to Bertron G. Harley and Edna B. Harley, Saco, Maine

Application September 26, 1937, Serial No. 164,618

6 Claims. (Cl. 298—22)

This invention relates to dumping vehicles equipped with load dumping mechanism, and more particularly it relates to improvements in actuating mechanism for the tiltable vehicle body of motor trucks.

A tilting mechanism of the type herein contemplated comprises a telescoping device or jack which operates under power normally derived from the vehicle engine.

10 Ramming and cam action respectively are the two mechanical principles to be discerned in representatives of this class of mechanism. The load lifting leverage inherent to a ram action device is found to be unfavorable or inefficient during the initial phase of the tilting operation owing to the unfavorable leverage or position of the ram relative to the body. The ramming action, however, becomes increasingly effective as the angular movement of the body proceeds in 20 the act of dumping.

In the cam action device, conditions of relative effectiveness are substantially the reverse of those in the ram type device, in that the cam action is particularly desirable during the initial 25 phase of tilting due to the great lifting power of its wedging effect, although on the other hand that effectiveness drops off during the remainder of the tilting movement.

My object therefore is to design a tilting mechanism in which effective operating leverages, lifting forces and stress reactions are established during all phases of the tilting operation, requiring a minimum of power or hydraulic operating pressure for the lifting or dumping. Other 35 objects are to design a tilting mechanism which can be readily adapted to existing or standard chassis and bodies.

To this end I propose a design in which both the ram and the cam action principle are combined in such a way that each becomes effective during that portion of the tilting movement for which it is best suited. That is to say, I devise a mechanism which exercises cam or wedge action during the initial phase of the tilting operation, 45 converting same into direct ramming effect during the balance of the tilting movement.

According to one feature, while I obtain the benefit of ram action in the latter portion of the tilting movement, I do away with conventional permanent pivotal connection between the ram and the box body by causing the ram at an intermediate point of the stroke to enter into temporary quasi-pivotal engagement with the box body. In distinction from ordinary ram 55 action devices therefore, the present construc-

tion permits hoisting the body off the chassis by extraneous means for the purpose of inspecting the mechanism underneath, without necessitating the removal of a pivot connection normally found in ram devices between the ram head and the body.

In a practical embodiment of my invention I arrange for a telescopic jack device to be mounted upon the truck chassis in such a manner that it will start the tilting operation by direct wedging 10 or camming action forcing the body away from the chassis for an initial period. At a suitable intermediate point of the stroke the advancing head of the jack will engage or be caught or intercepted in a hook shaped portion on the 15 rising body frame thus realizing a temporary quasi-pivotal connection between the jack and the body, that is to say, automatically changing from camming to ramming action of the jack device. The connection becomes self-securing 20 during the balance of the tilting movement of the body to prevent overtilting of the body in the process of dumping.

Other features relate to constructions of a tilting mechanism, which make it readily adaptable 25 to the structural conditions found in various types and sizes of chassis and vehicle bodies.

More particularly in one embodiment, ratio increasing linkage is interposed between the jack or ram rod or thrust member on the one hand, and the vehicle body and chassis on the other hand.

In view of left-hand, as well as right-hand power takeoff requirements, the present tilting mechanism is designed to be mountable to meet either condition. A gear pump associated and substantially unitary with the hydraulic cylinder has features which also make it readily adaptable 35 in that respect.

The invention is illustrated in the accompanying drawings which show two embodiments of the invention for illustrative purposes, although it is of the best embodiment that I know of at present.

Fig. 1 is a diagrammatic side view of chassis 45 and body in section and with the tilting mechanism and latch means therefor, in initial and final operating positions.

Fig. 2 shows an intermediate body lifting position of the mechanism of Fig. 1, with quasi- 50 pivotal connection about to be established.

Fig. 3 is a diagrammatic plan view of Fig. 1, showing a combination of three cam rails with three cam rollers, effective between the chassis and the body.

Fig. 4 is a diagrammatic side view similar to Fig. 1, with the addition of ratio-increasing linkage in the tilting mechanism and otherwise improved link construction.

5 Figs. 5 and 6 are motion diagrams showing various operating phases of the mechanism of Fig. 4. Fig. 1 illustrates the underlying idea of this invention broadly by showing characteristic operating positions in the procedure of tilting the truck body. Upon the supporting frame construction or chassis frame 10 a body 11 is pivotally mounted at 12 for tilting movement. A body tilting- or actuating mechanism generally comprises a hydraulic jack device, and an improved mechanism is herein shown to comprise an hydraulic jack cylinder or jack base member 13 extending substantially centrally and in the longitudinal direction of the chassis, and it is pivotally mounted as at 14 upon the chassis by 10 way of a transverse member 15. A ram-rod 16 telescopes into and out of the jack cylinder and it is preferably, although not necessarily, hydraulic pressure-controlled to effect its advancing and retracting operations. At its free end 15 ram rod 16 is provided with a crosshead 17 or the like carrying a set of suitably arranged cam rollers such for example as a set of three rollers including a pair of rollers 18 and 19 on the one hand, and a third roller 20 on the other hand 20 (see Fig. 3). Correspondingly the chassis frame 10 is provided with a pair of cam rails 21 and 22 straddling the chassis center line and having inclined cam faces 21a and 22a adapted to be engaged by the cam rollers 18 and 19, whereas the 25 body is provided with a third cam rail 23 arranged centrally with respect to the two other cam rails and adapted to be engaged by the central cam roller 20.

30 A hook portion 24 is fixed upon the underside 40 of the body 11 and shown to be associated with the third cam rail 23 and adapted to be engaged by the crosshead 17 of the ram rod 16.

The operation of the mechanism so far described is substantially clear from Fig. 1, in which 45 the body 11 is assumed to be loaded and at rest upon the chassis 10 as shown by its (full line) position A. At this time the swingable jack cylinder is in the full line position shown in Fig. 1, having its ram rod 16 withdrawn into the cylinder, and its crosshead or cam roller end resting upon the lower portion of the cam faces 21a and 22a of cam rails 21 and 22. Tilting operation is started by supplying to the hydraulic cylinder 13 hydraulic pressure as from an engine driven pump 50 (not shown), causing the ram rod 16 to advance. Consequently the cam rollers 18, 19 and 20 will enter into pressure engagement with the cam faces of their respective cam rails 21, 22 and 23 and thus through intrinsically powerful wedging 55 effect initiate the upward swinging movement of the body although under relatively low hydraulic pressure requirements. This wedging action maintains during the portion of highest resistance of the tilting stroke and until the cam rollers 60 have reached the end-portion of their respective cam rails or cam faces when the free end or crosshead 17 of the ram rod 16 will be intercepted by the hook portion 24 upon the body.

At this time, as the advancing ram rod 16 reaches a predetermined effective end portion of 70 its cam rails, the wedging action exercised upon the body will have been converted into straight ramming action inasmuch as the ram rod by way of the hook portion 24 has then entered into 75 a quasi-pivotal connection with the body 11.

Therefore continued advance of the ram rod will finish the tilting movement of the body until the latter reaches a predetermined end position B (shown in dot and dash) at an inclination which permits the load to slide off, thus permitting the body to unload itself.

It will thus be understood from the foregoing that the initial and heaviest resistance to load lifting is met according to this invention by powerful wedging action although requiring relatively low hydraulic operating pressure, while the diminishing load resistance during the continued upward movement of the body is met or sustained or overcome by direct ramming action.

Fig. 4 shows the tilting mechanism of Fig. 1 modified by the addition of ratio-increasing linkage, and thus rendered adaptable to a relatively greater variety of truck and body construction. The ratio-increasing linkage as shown in Fig. 4 15 comprises a swingable member 27 pivoted at 28 upon the chassis frame 29, and a connecting link 30 between the free end of the swingable member 27 and the body 31. The swingable member 27 is provided with a hooked portion 32 for the purpose set forth in connection with Fig. 1, and is 20 otherwise efficiently shaped to sustain maximum bending stresses as shown. Otherwise, in Fig. 4 the jack device is collectively designated by the numeral 33 and includes the hydraulic cylinder 34 and the ram rod 35. A set of cam rollers 36 is provided on the free end or head 37 of the ram rod, which rollers are 25 adapted to operatively engage upon stationary cam rails or members 38 fixed upon the chassis, and upon a corresponding movable cam member 39 as represented by the swingable member 27.

The operation and ratio-increasing effect of the modified construction is substantially self-explanatory from the showing of Fig. 4.

I claim:

1. In combination with a vehicle having a frame construction and a body pivotally mounted thereon and adapted to be moved from position of rest upon the frame construction to load dumping upwardly tilted position and vice versa; 45 an actuating mechanism for tilting the body, which comprises a jack device or expansible brace operative between the body and the frame construction, having a base member pivotally mounted upon the frame construction and an 50 advanceable and returnable thrust member telescoping with said base member and adapted to tilt said body when influenced in its relation to the base member, and further comprising suitably arranged cam portions provided upon said 55 frame construction and upon said body respectively, to be engaged by said thrust member to force the body away from said frame construction during an initial phase of the body tilting movement, a hook portion associated with the 60 body and adapted to receive and intercept the advancing head portion of said thrust member at an intermediate point of its body tilting stroke and so as to establish a temporary quasi-pivotal connection therewith enabling said thrust member 65 to continue by direct ramming action upon said body during the finishing of the tilting stroke.

2. An actuating mechanism according to claim 1, in which the quasi-pivotal connection becomes self-securing due to the relative rotation of the hook member about its quasi-pivot during the said balance of the tilting movement.

3. In a vehicle having a frame construction and a body pivotally mounted with respect thereto,

to and adapted to be moved from a position of rest upon the frame construction to upwardly tilted position and vice versa, an actuating mechanism for tilting the body, which comprises a 5 jack device operative between the body and the frame construction and having a base member pivotally mounted upon the chassis and an advanceable and returnable thrust member operated from said base member and adapted to tilt 10 said body, said mechanism further comprising a wedgelike cam portion mounted with respect to said frame construction and a companion wedgelike cam element serving as a track and pivotally movable with respect to the frame construction 15 and effective incident to its pivotal movement to tilt said body, namely, when forced away from the first mentioned cam portion, both said cam portion and said companion cam element designed and disposed to be engaged by said thrust member in a manner to force the body away from said frame construction during an 20 initial phase of the body tilting movement, a hook portion associated with said cam element and adapted to receive and intercept the head

portion of said thrust member at an intermediate point of its advancing movement, and further adapted to establish a temporary quasi-pivotal connection therewith and thereby to enable said thrust member to continue lifting said body by way of pivotal association therewith. 5

4. Mechanism according to claim 3, in which the companion element comprises a swingable member having its one end pivoted with respect to the frame construction and its other end movably connected with the body. 10

5. Mechanism according to claim 3, in which the companion cam element constitutes a member in a chain of ratio increasing means operatively extending between the frame construction 15 and the body.

6. Mechanism according to claim 3, in which the companion cam element comprises a swingable member having its one end pivoted with respect to the frame construction, with the addition of a link pivoted to the other end of said swingable member and to the tiltable body respectively. 20
